CLAIM

The ornamental design for a battery storage case having a foam insert for receiving a plurality of different sized batteries, as shown and described.

DESCRIPTION

FIG. 1 is a front elevational view of the battery storage case having a foam insert for receiving a plurality of different sized batteries showing my new design;

FIG. 2 is a rear elevational view thereof;

FIG. 3 is a right view thereof;

FIG. 4 is a left view thereof;

FIG. 5 is a top plan view thereof;

FIG. 6 is a bottom plan view thereof; and,

FIG. 7 is an isometric view thereof of the storage case in the open orientation illustrating the plurality of different sized battery apertures.
